SINGLE GAP RELAY

John C. Schuessler, West Covina, and Andrew O. Adams, Inglewood, Calif., assignors to Leach Corporation

Filed June 23, 1958, Ser. No. 743,924

8 Claims. (Cl. 317—188)

This invention pertains to a relay and more particularly to a relay having dual coils and a single working gap.

It is often necessary to provide a relay in a location where excessive bulk or weight cannot be tolerated. This may be, for example, in airplanes or missiles where space and weight always are at a premium. In many instances, it may be found that a relay of the conventional single coil construction has insufficient holding force for the requirements at hand. The problem is made more acute by the fact that the relay in such installations will be subjected to a variety of external forces, such as gravitational and vibrational forces, which add to the force necessary in moving and holding the armature of the relay. Such forces also have required the use of a relatively stiff spring acting on the armature to bias it away from the closed position and prevent inadvertent actuation of the relay. Therefore, the relay coil must overcome considerable spring force when it is energized to close the relay. Also, even the stiffest springs may resonate with vibrations imposed and allow the relay to close prematurely.

In an effort to alleviate this, it has been proposed to provide a relay having two coils operating a single armature. Unfortunately, however, this does not double the holding power of the relay, but results only in the theoretical maximum of about fifty-nine percent increase in available ampere turns. This relatively small increase, despite virtually doubling the size and weight of the relay results because the provision of a second coil also adds a second working air gap into the system. By far, the greatest loss in relay closing force occurs at the air gap. Heretofore, regardless of the construction or arrangement of the armature in the prior art devices, two gaps have been present, one at each of the coil cores. These double coil relays also may be adversely affected by gravitational forces.

This invention provides a double coil relay having only a single working gap. As a result virtually a one hundred percent increase in available ampere turns is obtained. This is accomplished by a unique arrangement of an armature having a large area closely adjacent and pivoting relative to an enlarged end of the core of one coil so as to move to a position of contact with the end of the core of the second coil. The only working gap present is between the armature and the second core. Furthermore, the armature is counterbalanced, which avoids closing under externally applied forces and makes unnecessary the use of a stiff spring for loading the armature.

Therefore, it is an object of this invention to provide a single gap, double coil relay having maximum closing force.

Another object of this invention is to provide a relay which is not adversely affected by vibrational or gravitational forces.

An additional object of this invention is to provide a relay of compact and lightweight construction.

Yet another object of this invention is to provide a relay having a counterbalanced armature pivoted rela-

2

tive to one core end for movement to engage a second core end.

These and other objects will become apparent from the following detailed description taken in connection with the accompanying drawing in which:

Fig. 1 is a top plan view of the relay of this invention,

Fig. 2 is a sectional view taken along line 2—2 of Fig. 1,

Fig. 3 is a sectional view similar to Fig. 2 of a modified form of the invention having a unitary armature and offset coils, and

Fig. 4 is a fragmentary sectional view of a further modification in which the armature is unitary and includes an offset.

Referring to Figs. 1 and 2 of the drawing, the relay of this invention includes coils 1 and 2, which are disposed in an aligned, parallel, side-by-side arrangement. Conventional cores 3 and 4 are within the coils, but are provided additionally with bottom shoulders 5 and 6 and outer threaded shanks 7 and 8. These shanks of the cores extend through yoke 9 of magnetic material which abuts one end of each coil, and are secured thereto by nuts 10 and 11. The yoke, therefore, physically connects the coils and also joins their magnetic circuits.

25 A frame 12 of non-magnetic material, such as brass, engages the top ends of the coils and includes a bottom wall 13 receiving cores 3 and 4 which project therethrough. Enlarged flat core heads 14 and 15 are disposed above bottom wall 13 of the frame. Core head 14 of core 3 is the larger of the two and extends laterally at 16 to a position adjacent to be spaced from square core head 15.

A flat armature 17 is disposed above core head 14 on extension 16 thereof and is pivoted with respect thereto.

35 This may be accomplished by providing a transverse pin 18 interconnecting upwardly extending parallel sides 19 and 20 of the frame. This pin passes over armature 17 and holds the armature adjacent extended portion 16 of core head 14. A suitable journal arrangement such as

40 member 22 is soldered or otherwise connected to armature 17 and passes over pin 18. This prevents lateral displacement of the armature and maintains the armature in proper relationship with core head 14. Pin 18 and journal 22 hold the armature very close to core head 14, but slightly spaced therefrom to allow the armature 45 to pivot freely about the pin.

In order to permit the pivotal movement of the armature, it is bent as illustrated at location 23 beneath pin 18. Furthermore, the armature is in two sections integrally attached together. Portion 24, which extends over core 50 head 15, is of magnetic material such as iron. The other portion extending back over core head 14 is nonmagnetic and may be of stainless steel. The magnetic portion of the armature includes the bent section 23, which is enlarged laterally so that a sizable area exists between core head 14 and the armature.

Accordingly, when the coils are energized the path of the magnetic flux is that indicated by the arrows, passing through the cores and the yoke to armature 14 at location 23. The large area at 23 between the armature and the core means that there is an efficient flux transmissive path at this point despite the small distance between the armature and core head 14. For all practical purposes this minute space—which may be around .002 inch—does not exist in the system as far as losses in efficiency 60 are concerned. As a result, only one working gap 27, between armature portion 24 and core head 15, is present in the system. This means that even though two coils have been provided for the relay, only a single working gap is required and virtually a one hundred percent increase in available ampere turns is obtained.

The magnetic flux pivots the armature to the position

shown in phantom where it is in engagement with core end 15. If the armature were not held a small distance away from core head 14, it would be drawn tightly against this core as well when the coils were energized. This would cause sliding between the armature and core 14 when the armature pivoted about pin 18. Therefore, the frictional force between the armature and core 14 would prevent the armature from moving smoothly and rapidly to its closed position.

Nomagnetic portion 25 of the armature serves as a counterbalance so that the armature is not affected by gravitational forces. This portion of the armature extends back over core 14 and so adds practically no additional bulk to the unit. By being of nonmagnetic material no magnetic force tends to draw the armature toward core head 14 when the coils are energized. With the armature weighing approximately the same on both sides of the fulcrum, only a light wire spring 28 is required to hold the armature in its normal position away from core head 15. This spring may be wound around pin 18 as illustrated, including one portion 29 bearing against the top of portion 25 of the armature while the other end 30 extends to opening 31 in side 19 of the frame. A slight additional spring force can be obtained by moving end 30 upwardly from opening 31 to opening 31a. Thus, there is no necessity of including a stiff spring in the system to engage the armature. No difficulty is encountered from a spring resonating with vibrations in the system because the armature is counterbalanced, and practically all of the coil force is used in moving and holding the armature rather than overcoming spring force.

It is obvious, of course, that the relay in this invention may be used in a variety of ways in the manner of any conventional relay. For example, contacts may be carried by armature 17 for use in another electrical system.

According to the modification of Fig. 3, the armature is a unitary member, being entirely of magnetic material. This has the advantage of simplicity and economy of construction of the armature. However, in order to avoid a magnetic pull to the second coil, the coils are disposed in an offset arrangement as illustrated. Thus, as seen in Fig. 3, armature 32 is pivotal with respect to projection 33 of core end 34 which extends upwardly as well as laterally from the coil end so that a relatively large space 35 exists between counterbalance portion 36 and this core head. A transverse pin stop 37 prevents armature 32 from pivoting beyond the position illustrated. Of course, bottom wall 40 of the frame and yoke 41 also are offset in the construction of this unit. Large gap 35 assures that only negligible magnetic force will be exerted between the counterbalance portion of the armature and core end 34.

In the embodiment of Fig. 4, the coils remain in their aligned relationship, but armature 42 is offset in construction, being of a generally Z shaped configuration to avoid magnetic pull to core head 14. This results in a wide gap 43 between counterbalance section 44 and core head 14 so that the armature is not attracted to that core. Transverse pin 45 acts as a stop to prevent further reverse movement of the armature, and journal portion 46 must be slightly modified in shape from the journals used in the previous embodiments.

It is apparent from the foregoing, therefore, that we have provided an improved relay design whereby only a single working gap is present, yet two coils are included. This relay construction provides twice the force of single coil relays and much more force than dual coil relays having two gaps. In addition, the armature is fully counterbalanced without materially adding to the size of the device.

The foregoing detailed description is to be clearly understood as given by way of illustration and example only, the spirit and scope of this invention being limited solely by the appended claims.

We claim:

1. A relay comprising a duality of coils having cores

therein and arranged in adjacent relationship, magnetic flux-conductive means interconnecting the cores of said coils at one end thereof, an armature, and means mounting said armature in a magnetic flux-conductive working 5 gap-free relationship on the opposite end of one of said cores so that said armature is pivotal relative to said opposite end between a position remote from the opposite end of the other of said cores and a position in contact therewith, whereby only a single working gap is provided in the magnetic circuit of said relay.

2. A relay comprising a coil assembly including a duality of coils each having a core therein, a yoke interconnecting said cores at one end of said coil assembly for providing a magnetic flux conductor therebetween, a core 10 extension at the opposite end of said coil assembly projecting from the first of said cores toward the other, an armature, and means pivotally mounting said armature with respect to said core extension with the pivot point adjacent thereto and said armature in a working gap-free 15 flux-conductive relationship therewith so that said armature extends over the second of said cores and is movable relative thereto between a position remote from said second core and a position in engagement therewith, whereby only a single working gap is provided in the magnetic flux 20 circuit of said coils.

3. A device as recited in claim 2 in which said armature is provided with a counterbalance portion projecting from said pivotal mounting means away from said second core and in a nonflux-conductive relationship with said first 25 core, thereby to balance said armature on said core extension.

4. A device as recited in claim 3 in which said coils are axially offset with respect to each other whereby said counterbalance portion is remote from said first core for 30 all positions of said armature and maintained in said nonflux-conductive relationship therewith.

5. A relay comprising an assembly of a duality of coils in a side-by-side parallel relationship, a central core element in each of said coils, a yoke of magnetic material 35 interconnecting said core elements at one end of said coil assembly, the core of the first of said coils having a relatively wide extension projecting laterally therefrom to a position closely adjacent and spaced from the second of said cores at the opposite end of said coil assembly, and an armature, said armature including a portion of magnetic material closely adjacent and pivotal relative to said extension in a working gap-free relationship therewith, said portion projecting over said second core and movable between a position remote therefrom and a position in engagement therewith, said armature further including a counterbalance portion projecting over said first core in a nonflux-conductive relationship therewith.

6. A relay comprising a pair of coils in a side-by-side spaced parallel relationship, an axially disposed core 40 element in each of said coils, a yoke of magnetic material interconnecting said cores at one end of said pair of coils, a frame of nonmagnetic material at the opposite end of said pair of coils, said frame having a bottom wall and parallel sides projecting therefrom, each of 45 said core elements having a relatively broad flat portion above said bottom wall, the flat portion for the first of said cores being larger than that of the second of said cores and projecting laterally between said sides to a position closely adjacent and spaced from the flat portion of the second of said cores, an armature, said armature having a flux-conductive portion of magnetic material provided with a relatively large area in juxtaposition and a working gap-free relationship with said laterally extending portion and pivotal relative thereto, 50 and projecting therefrom over the flat portion of the second of said core elements for movement between a position remote therefrom and a position in engagement therewith, said armature further having a counterbalance portion of nonmagnetic material connected to said flux-

conductive portion and projecting over said flat portion of said first core.

7. A relay comprising a duality of coils in spaced parallelism, an axially disposed core element in each of said coils, each of said core elements having a shoulder and a threaded shank projecting therebeyond at one end thereof, a yoke receiving each of said shanks for interconnecting said cores, said yoke being in engagement with said shoulders and one end of each of said coils, a nut on each of said shanks for securing said yoke thereto, a frame at the opposite end of said core elements, said frame having a base wall and two parallel side walls projecting from one surface thereof, the opposite surface of said base wall engaging the ends of said coils, said core elements extending through said base wall and being provided with enlarged flat head portions engaging said one surface of said base wall, one of said flat head portions being laterally enlarged and extending to a position closely adjacent and spaced from the other of said head portions, an armature, said armature having a portion of relatively large area, a pivot pin interconnecting said side walls and extending over said armature at said portion of relatively large area, said armature including a journal receiving said pin and maintaining said portion of relatively large area closely spaced from said laterally enlarged portion and pivotal with respect thereto, said armature having two sections the first of which is of magnetic material and includes said portion of relatively large area and extends therefrom to a position above the flat head portion of the other 30

5

of said core elements for movement upon pivoting of said armature between a position remote therefrom and a position in engagement therewith, the second section of said armature being of nonmagnetic material and extending from said portion of relatively large area to a position above the flat head portion of the first of said core elements for counterbalancing said armature, and a relatively light spring member engaging said armature and biasing said armature to said remote position.

8. A relay comprising a duality of coils having cores therein, magnetic flux-conductive means interconnecting the cores of said coils at one end thereof, said cores being provided with flat core heads on the opposite ends thereof, the core head of one of said cores being larger than the core head of the other and extending laterally toward said core head of said other core, an armature adjacent and in working gap-free flux-conductive relationship with said larger core head and pivotal relative to said larger core head between a position remote from the smaller of said core heads to a position in engagement therewith, and a counterbalance on said armature for balancing the same and precluding movement thereof in response to externally applied forces.
